HANDLE FOR GEAR SHIFT LEVER

John A. Watson, Royal Oak, Mich., assignor to
Hurst-Campbell, Inc., Warminster, Pa., a corpora-
tion of Pennsylvania

Filed Dec. 1, 1966, Ser. No. 4,886

Term of patent 14 years

(Cl. D14—6)

FIG. 1 is a front elevational view of a handle for gear shift lever embodying the design.

FIG. 2 is a left-hand elevational view of FIG. 1.

FIG. 3 is a right-hand elevational view of FIG. 1.

FIG. 4 is a top plan view of the handle for gear shift lever shown in FIG. 1.

FIG. 5 is a rear elevational view of the same.

FIG. 6 is a bottom plan view of the handle for gear shift lever.

The shift lever shown fragmentarily and in broken lines is included for illustration purposes only.

I claim:

The ornamental design for a handle for gear shift lever, as shown and described.
